UNITED STATES PATENT OFFICE.

DUNNING S. WILSON, OF LOUISVILLE, KENTUCKY, ASSIGNOR TO GRAND CHAPTER OF PHI CHI MEDICAL FRATERNITY, OF LOUISVILLE, KENTUCKY, A CORPORATION OF KENTUCKY.

DESIGN FOR A FRATERNITY EMBLEM.

No. 38,554.

Specification for Design.

Patented May 14, 1907.

Application filed April 1, 1907. Serial No. 365,895. Term of patent 14 years.

To all whom it may concern:

Be it known that I, DUNNING S. WILSON, a citizen of the United States, residing at Louisville, in the county of Jefferson, State of Kentucky, have invented a certain new, original, and ornamental Design for Fraternity Emblems, of which the following is a specification, reference being had to the accompanying drawing, forming a part thereof.

The figure is a front view of a fraternity emblem, showing my new design.

I claim:

The ornamental design for a fraternity emblem, as shown.

DUNNING S. WILSON.
